Henry A. Hayden INVENTOR.

UNITED STATES PATENT OFFICE.

HENRY A. HAYDEN, OF WESTFIELD, NEW JERSEY, ASSIGNOR TO HAYDEN INVENTIONS CORPORATION, OF WESTFIELD, NEW JERSEY, A CORPORATION OF NEW JERSEY.

CLEANING IMPLEMENT.

1,313,184.

Specification of Letters Patent. Patented Aug. 12, 1919.

Application filed May 16, 1918. Serial No. 234,904.

To all whom it may concern:

Be it known that I, HENRY A. HAYDEN, a citizen of the United States, and a resident of Westfield, in the county of Union and 5 State of New Jersey, have invented certain new and useful Improvements in Cleaning Implements, of which the following is a specification.

This invention relates to improvements 10 in cleaning implements, and more particularly aims to provide a cleaning implement adapted to constitute a duster or mop, as desired, having novel advantages.

These advantages are, in the case of the 15 mop, that there is provided a support and mop, of such a nature that the mop may be readily and easily mounted on and taken off the support; that the mop, when mounted on the support, will be very securely and 20 dependably mounted thereon; that the mop when on the support may be used very roughly and yet present flexible portions for cleaning heretofore inaccessible corners and the like; that the mop may as a complete 25 unit be readily and easily washed, wrung or otherwise cleaned, either on or off the support; and that the cost of labor and materials necessary for constructing the mop will be almost inconsiderable.

30 The advantages are the same, in the case of the duster, and in addition, that the duster may be combed and cleaned of dust readily and easily without detachment from the support, and that the duster is so constructed as to present no parts which by any chance may mar woodwork or the like even when the duster is recklessly used.

Since the support may interchangeably be used with the mop and the duster referred 40 to above in exemplification of the invention, the support will be described herein in combination with such a mop and such a duster. The mop and duster have these features in common, to-wit, a flexible backing for the 45 cotton strands, or other suitable work-contacting elements hereinafter referred to merely as the strands, such backing being preferably deformable, especially when removed from the support, and of tubular 50 character to glove the support.

The cardinal object of the invention is to provide an arrangement of the general character described in the last paragraph, such, for instance, as shown and described in my previous patent No. 1,002,268; but one having the advantages that, while preserving the same simplicity of construction as before, the tubular backing will not be permitted to sag in the center when loaded with dust and dirt or wetted, and will be 60 prevented from working around on the support to gradually shift the strand-carrying face partially or entirely away from the underside of the support. These objects are attained by providing a plurality of substantially parallel open-ended pockets within the tubular backing, together with a single-piece bent-wire support shaped for entrance within both of these pockets simultaneously. 70

The invention will be more clearly understood from the following description when taken in connection with the accompanying drawing illustrating the invention, wherein:

Figure 1 is a side elevation of a mop or 75 duster mounted on and tied to the support;

Fig. 2 is a top plan view of the parts shown in Fig. 1;

Fig. 3 is a transverse vertical section, taken on the line 3—3 of Fig. 2; 80

Fig. 4 shows the two reversely looped tapes in perspective, with only lines of stitching shown on the tapes, illustrating the dissimilar projecting tape lengths;

Fig. 5 is a somewhat diagrammatic view, 85 showing a spread out fabric blank for the backing, the folding lines of the blanking being indicated in dot and dash lines, and the tapes only being shown secured to the backing, with such tapes arranged so that 90 the seam later formed by the side edges of the blank will lie on the upper face of the backing;

Fig. 6 is a view similar to Fig. 5, except that the tapes are so arranged that such 95 seam will lie on the under face of the backing;

Fig. 7 is a fragmentary view, showing a modification of a detail of construction.

Referring to Figs. 1 to 4, which may illus- 100

trate a mop or duster, the backing is composed of a rectangular piece of fabric bent over as shown to form the under face 7 and the upper faces 8 and 9. The backing is 5 preferably inturned at its end edge-portions 10, for reinforcement, and these inturned edge-portions are stitched fast as indicated at 11. The side edges of the upper face portions 8 and 9 are secured to the end face 10 7 at points along the central line of the backing, in any suitable way, to provide two open-ended pockets as shown most clearly at 12 in Fig. 3. Such securing means may comprise a line of ordinary stitching, not 15 shown, or a plurality of staples 14 as illustrated.

Two rows of strands 15 are secured to the under side of the backing as shown; the strands of each row being preferably contained 20 between upper lengths 16 and lower lengths 17 of cotton tapes arranged as illustrated in Fig. 4, the upper lengths 16 lying below the backing and above the middles of the strands and the lower lengths 17 lying 25 below the middles of the strands, as indicated in Fig. 3. In Fig. 4, the dot and dash line 18 may define the end 19 of the backing shown in Fig. 2; and it will be noted that rearwardly of the rear end of the backing, the length 16 of one of the tapes is 30 prolonged at 16'; and the length 16 of the other tape is prolonged at 16'' for a greater distance.

The support for the mop or duster comprises 35 a single wire member including a shank 19 formed of the terminal lengths of the wire, arranged side by side, and two tine portions 20 formed of intermediate lengths of the wire each reversely looped as 40 shown in Fig. 2. The shaft 19 of the support is offset at an obtuse angle from the plane of the tine portions 20 and is secured permanently into the lower end of a long wooden handle 21 and surrounded by a ferrule 22.

To mount the mop or duster on the support, as to interchange one for the other in a cleaning implement comprising the support and a mop and duster, the tine portions 50 20 of the support are inserted into the open ends of the pockets 13 at the end of the backing from which dangle the as yet untied lengths 16' and 16'', the parts becoming then arranged as shown clearly in Fig. 2, but 55 with the lengths 16' and 16'' not yet tied into the single-bow knot illustrated. The tape lengths 16' and 16'' are then crossed in back of the ferrule and brought around to cross again in front of the ferrule, and 60 tied into a knot as shown, the length 16'' being long enough to permit it to form the single bow 23.

The mop or duster is thus instantly applied to the support and very securely held,

the line of staples 14 falling between the 65 parallel spaced pockets 13. Attention is directed to the fact that the tips 20' (Fig. 2) of the tine portions 20 fall short of the outer ends of the pockets 13, so as to arrange the outer portion of the backing free of any 70 rigidifying support, that is, so that an end portion of the backing will have maximum flexibility above the work contacting elements beyond the outer end of the support.

In operation, the mop or duster has all 75 the advantages above enumerated, as will be apparent. When a duster is to be provided, the fabric of the backing is preferably a textile fabric, coated with rubber or a suitable composition on its outer surface, 80 and may desirably be black oil cloth; and the strands are black cotton duster strands of the familiar kind. When a mop is to be provided, the fabric backing is preferably of non-rotting canvas or duck, and of buff 85 color, and the strands are natural color, unbleached cotton mop strands of the familiar kind. Whether a mop or duster, the cleaning implement may be washed, wrung, combed, dusted or otherwise cleaned, with- 90 out removal from the support; each row of strands being handled separately.

Reverting to Fig. 2, it may be found desirable in some cases to provide, instead of the knot-affording tape-lengths (the lengths 95 16' and 16'' of Fig. 4), mounting means for the mop or duster for coacting with a part of the bent-wire support other than the shank portion thereof. For instance, the upper faces 8 and 9 of the backing may be 100 apertured and reinforced with metal eyelets as indicated at 24, the under face 7 may be similarly apertured and eyeleted at points below the points 24, and coil-spring devices 25 or the like provided and used as 105 shown to mount the mop or duster on the support. Here the devices 25 will have hooked opposite ends for engaging with the eyeleted apertures 24 as indicated.

Reverting to Figs. 3 and 4, it may be 110 found desirable in some cases to provide, instead of the lines of stitching shown in Fig. 4 for affixing the tapes and strands to the under side of the backing, a series of staples 26 for the purpose as shown in Fig. 115 7, similar to the staples 14.

I claim:

1. A cleaning implement comprising a flexible backing including a plurality of side-by-side substantially parallel pockets both 120 pockets being open-ended along a line substantially perpendicular to the lengths of the pockets, there being a plurality of work-contacting elements on the outside of the backing, and a rigidifying support comprising a member formed of a single piece of bent wire and including a shank portion and two substantially parallel tine portions 125

offset from the shank portion with the space between the tine portions substantially opposite the shank portion, each of said tine portions for entering one of said pockets.

5 2. A cleaning implement as described in claim 1, wherein the tine portions are each formed of a reversely looped length of wire

and the shank portion is formed of two side-by-side arranged terminal lengths of the wire.

10 Signed at New York in the county of New York and State of New York this 13th day of May, A. D. 1918.

HENRY A. HAYDEN.
